APPARATUS FOR PUMPING LIQUID IN THE
TREATMENT OF MINERAL ORES

Herbert William Benjamin Gardiner, Kenton,
and Alexander Bloomer Jackson, Wembley
Hill, England, assignors to The General Elec-
tric Company Limited, London, England

Application March 17, 1933, Serial No. 661,204,
and in Great Britain February 15, 1932

2 Claims. (Cl. 103—215)

This invention relates to the treatment of mineral ores, for example by froth flotation, cyanidation and the like processes, and more particularly to apparatus for feeding liquids, such as reagents, 5 during the treatment of mineral ores.

In such treatment it is often essential that the quantity of liquid being fed should be accurately known and that the quantity should be adjustable. One object of the present invention is to 10 provide improved feeding apparatus in which this adjustment is easily effected. Another object is to prevent oil used for lubricating moving parts of the apparatus from coming in contact with the liquid being fed. Many of the liquids used 15 carry matter in suspension and it is a further object of the invention to ensure that such liquids are agitated during feeding to prevent the matter from settling out.

Apparatus for feeding liquids during the treatment of mineral ores, according to the present invention, comprises a pump adapted to feed liquid from a supply tank and means adapted to be adjusted to different positions to vary the rate of feed, definite known quantities of liquid 20 being fed for each of the positions of the said means. The liquid may be fed under pressure by the pump thereby ensuring that the rate of delivery is substantially independent of the viscosity of the liquid. Thus a definite volume of 25 liquid may be withdrawn from the supply tank and a proportion of that volume may then be forced by the pump through the outlet or delivery valve of the pump, the said adjustable means being adapted to vary the said proportion of 30 the volume.

The pump may be adapted to force liquid back towards the supply tank and the said adjustable means to vary the period during which the pump can force the liquid back. The adjustable means 40 may vary the period during which the inlet valve to the pump is closed.

Conveniently the pump may draw liquid out of the supply tank and then tend to force it back again and the inlet valve when closed may prevent the return of the liquid to the tank and force it to flow through the outlet valve which may be biased to the closed position. In such an arrangement the inlet valve may comprise a slide valve and the adjustable means may vary the 45 point in the stroke of the slide at which closing of the valve opening occurs.

The invention will now be described by way of example, with reference to the accompanying drawings of pumping apparatus for feeding liquids during the treatment of mineral ores. Fig-

ure 1 of the drawings is a side elevation of the apparatus, Figure 2 is a section through the casting on the line II—II of Figure 1, Figure 3 is a section on the line III—III of Figure 2, the pointer (not shown in Figure 2) for indicating the rate of feed being shown broken away in parts to show details of construction, Figure 4 is a section on the line IV—IV of Figure 3 and Figure 5 is a section on the line V—V of Figure 3 with part broken away to show a section on the line VI—VI of Figure 3.

As shown the apparatus comprises a compartment 4 containing the pump mechanism and a compartment 5 containing mechanism for operating the pump and controlling the rate of feed. The pump is provided with an inlet 1 which can be connected to the supply tank and an outlet 2 to which the delivering pipe is attached. The pump is operated through a driving shaft 3 which is rotated at constant speed, for example by an electric constant speed motor. Mounted on the outside of the compartment 5 is a pointer 6 which can be moved over a scale 7 to adjust the rate at which the pump delivers liquid through the outlet 2.

The pumping mechanism comprises two plungers 8 and 9 arranged to reciprocate respectively in two vertical barrels 10 and 11 drilled out of a metal body 12; the plunger 9 and barrel 11 are of slightly larger diameter than the plunger 8 and barrel 10. The two barrels 10 and 11 are connected together adjacent to their lower ends by a horizontal duct 13, whilst the barrel 10 is also connected to the inlet 1 by a horizontal duct 14; the plunger 8 reciprocating in the barrel 10 thus forms an inlet valve for cutting off the communication between the ducts 13 and 14. The lower end of the barrel 10 is connected by a by-pass 15 to the duct 14, so that liquid trapped in the lower end of the barrel 10 can escape into the duct 14 during the latter part of the down stroke of the plunger 8. The plunger 9 reciprocating in the barrel 11 acts as a pump for drawing liquid from the supply tank along the duct 14 into the duct 13 and then forcing it through a spring closed ball delivery or outlet valve 16 into a horizontal duct 17 leading to the outlet 2.

The two plungers 8 and 9 are operated from the same cam shaft 18 by means of cams 21 and 23 and rockers 22 and 24. The cam shaft 18 is arranged in the container 5 and is driven through worm reduction gearing 19 by the driving shaft 3. Arranged in the same container 5 is a cranked shaft 20 on which the rockers 110

22 and 24 of the two plungers 9 and 8 are pivotally mounted, the rocker 24 of the inlet valve plunger 8 only being mounted on the cranked portion 25 of the shaft 20. One end of this 5 shaft 20 protrudes from the container 5 and is rigidly attached to the pointer 6 which may be moved by hand over the scale 7 arranged on the outside of the container. Movement of this 10 pointer 6 thus rotates the cranked shaft 20 and so raises and lowers the pivoted point of the valve plunger rocker 24 without affecting the position of the pivoted point of the pump plunger rocker 22 and so varies the timing of the inlet 15 valve to vary the rate of feed. The scale 7 over which the pointer 6 moves may be calibrated to indicate the volume of liquid being fed per minute, or the different positions on the scale may be numbered and the rate of delivery be obtained from a calibration chart.

20 One end of each rocker bears against one of the cams 21 and 23 mounted on the cam shaft 18 and is either pressed against the cam by means of a spring or, as shown, is positively coupled to the cam by a member 26 which embraces the cam. The cam 23 operating the valve 25 plunger 8 leads the other cam 21 by approximately ninety degrees and, if desired, means may be provided for varying this lead thereby enabling the rate of feed to be varied by varying the 30 timing of the inlet valve relatively to the pump plunger.

The other end of each rocker is coupled to the top end of its associated plunger by means of a horizontal pin 27 engaging a horizontal slot 35 28 in the top end of the plunger, in which slot the pin 27 is free to slide horizontally. The compartment 5 containing the pump operating mechanism is partly filled with oil for lubricating the moving parts of the mechanism and a 40 partition 29 is arranged between the two compartments to prevent oil getting into contact with the liquids being pumped. The rockers 22 and 24 are suitably shaped to pass over the top of this partition through slots 30 to their respective 45 plungers.

The compartment 4 containing the pump mechanism is removably attached to the other compartment 5 by means of a spindle 31 projecting horizontally from the latter compartment 50 5 and to which the former compartment 4 is secured by means of a screw 32 having a milled edge. The pumping mechanism can thus be easily removed for cleaning purposes by removing the milled screw 32 and sliding the top ends 55 of the plungers clear of the pins 27 on the rockers. Furthermore the part containing the inlet and outlet 1 and 2 may be removed in a similar manner from the compartment 4 by removing a milled screw 33.

60 In operation the inlet 1 is connected to a supply tank containing liquid which it is required to feed in definite known quantities for the treatment of mineral ores, for example the liquid may be froth flotation reagents and the 65 pump may serve to feed it through the delivery pipe to froth flotation cells. The pointer 6 is then set to the quantity which it is desired to deliver per minute and the motor driving the pump is started up. When the plunger 9 rises 70 in the barrel 11, liquid is drawn into the duct 13 and barrel 11 past the inlet valve. When the plunger 9 commences to descend again it forces this liquid back along the supply pipe towards the supply tank until the inlet valve closes, 75 since the head of liquid is not sufficient to open

the outlet valve 16 against the pressure of the valve spring. When however the inlet valve is closed by the descending plunger 8, which is ninety degrees ahead of the plunger 9, the descending plunger 9 forces the liquid entrapped in the duct 13 and barrel 11 through the outlet valve 16 to the outlet 2 until the inlet valve is again opened by the plunger 8 rising.

It will thus be seen that during each cycle 80 of the plunger 9 a definite quantity of liquid is forced through the outlet valve dependent on the portion of the cycle during which the inlet valve is closed, so that the rate of feed may therefore be varied by varying the portion of the cycle during which the inlet valve is closed by rotating the cranked shaft 20 by means of the pointer 6 to raise or lower the pivoted point of the rocker 24 to vary the distance the plunger 8 slides past the valve opening. The scale 7 may be calibrated, for example in cubic centimetres per 90 minute, so that for any position of the pointer 6 on the scale 7 the pump feeds liquid at a definite and known rate, which is substantially independent of the viscosity of the liquid. This definite calibration is possible owing to the liquid 100 being fed through the outlet valve under pressure, instead of by the usual form of gravity feed in which the liquid is allowed to drip.

Many of the liquids used, and more particularly 105 some of the reagents used in froth flotation processes contain matter in suspension, and it will be seen that in the arrangement described above some of the liquid is pumped back along the supply pipe so that a surge is set up and the liquid is well agitated during feeding and matter 110 in suspension is prevented from settling out.

Furthermore in froth flotation processes it is often necessary to change over from one reagent to another and this may be done very rapidly with the arrangement described above. Thus by having a spare pump mechanism the compartment containing pump mechanism which is coated with one reagent may be removed in the manner hereinbefore described, and the spare clean pump mechanism inserted in its place for pumping 120 another reagent. Owing to the simple construction of the pump mechanism it may easily be cleaned, whilst it is unnecessary to clean the mechanism in the other compartment since this does not come in contact with the liquid being 125 fed.

When feeding liquids carrying a large quantity of matter in suspension it may be found that the outlet valve is liable to become clogged, in which case this valve may be replaced by a slide valve 130 operated by the cam shaft in a similar manner to the inlet valve.

If the pump is to be used for pumping liquids of a corrosive nature it is necessary to form those parts of the pump which come in contact with 135 the liquid, of a non-corrosive material. Thus the plungers 8 and 9 may be made of stainless steel or of ordinary steel coated with a suitable ebonite-like material, whilst the body 12 may be made of non-corrosive alloy, or of any suitable 140 metal and the barrels and ducts lined with a suitable ebonite-like material, or the entire body may be made of ebonite-like material. A suitable ebonite-like material which may be used is the material known as "Dexonite".

145 We claim:—

1. Apparatus for pumping liquids in the treatment of mineral ores comprising a compartment providing an oil bath, a plunger-block on the outside of said compartment having bores in which 150

2. Apparatus for pumping liquids in the treatment of mineral ores comprising a plunger-block provided with bores in which a pump plunger and a slide valve respectively are arranged to reciprocate, a compartment having means therein for reciprocating said plunger and the slide valve in predetermined sequence, said means including rocker arms extending through the wall of the compartment to which said plunger block is detachably secured, separable sliding connections between the rocker arms and the plunger and slide valve respectively to permit separation thereof when the plunger block is detached from said wall and means for removably securing said plunger block to said wall of the compartment. 80
